UNITED STATES PATENT OFFICE.

ALFRED J. FLAUDER, OF BRIDGEPORT, CONNECTICUT.

DESIGN FOR A SALT AND PEPPER SHAKER.

Application filed May 26, 1928. Serial No. 26,868. Term of patent 7 years.

To all whom it may concern:

Be it known that I, ALFRED J. FLAUDER, a citizen of the United States, and a resident of Bridgeport, in the county of Fairfield and State of Connecticut, have invented a new, original, and ornamental Design for a Salt and Pepper Shaker, of which the following is a specification, reference being had to the accompanying drawing, forming a part thereof, and in which—

Fig. 1 shows a top plan view of a salt and pepper shaker embodying my new design;

Fig. 2 is a side elevation of the same; and Fig. 3 shows an edge view.

I claim:

The ornamental design for a salt and pepper shaker substantially as shown.

Signed at Bridgeport, in the county of Fairfield and State of Connecticut, this 25th day of May, 1928, A. D.

ALFRED J. FLAUDER.
